United States Patent Office.

CHARLES S. H. FOSTER, OF DEER ISLE, MAINE.

Letters Patent No. 88,026, dated March 23, 1869.

MACKEREL-LATCH

The Schedule referred to in these Letters Patent and making part of the same.

To all whom it may concern:

Be it known that I, CHARLES S. H. FOSTER, of Deer Isle, in the county of Hancock, and State of Maine, have invented a new and useful Mackerel-Latch; and I do hereby declare that the following is a full, clear, and exact description of the construction and operation of the same, reference being had to the accompanying drawings, making a part of this specification, in which drawing is a perspective view of my invention, secured to a vessel's rail.

In "mackerel-fishing," each man has his allotted berth, being from thirty to thirty-six inches of the rails, changing from side to side as the vessel sails on one or the other tack, each fisherman having two lines, which he is required to keep within the limits of his berth, in order that they may not get entangled with those on either side.

Whatever device may be employed to confine the lines within the prescribed limits, it is indispensable that the line can be instantly detached, in case of injury, in order that another may be substituted for it.

Owing to the precarious and uncertain habits of mackerel, when biting, it is necessary that their biting-moods be taken advantage of to the utmost.

The nature of my invention consists in a bar, or stock of wood, which is secured to the rail by screws, or other suitable means, having two grooves, or channels for the lines, and provided with metallic latches, arranged to hold the lines securely closed, and to be instantly released when the lines require liberating.

In the drawings

A represents the vessel's deck;
B, the bulwark; and
C, the rail.
D is the stock of the latch, and
a a are two metallic latches, which are pivoted to bar D by the rivets b b.
c c are the lines, made fast to the cleats d d, secured to the bulwarks. The lines c c pass through the grooves cut across the face of stock D, as shown.

The pivot-ends of the catches are formed with the upper corner rounded, to allow the catch to be opened, as shown, while the opposite end is cut at an angle, relatively to their sides and edges, so as to shut into the recesses cut in stock D, as shown.

In practice, the lines are first made fast to the cleats d d, and are then carried up, and secured in the latch, as shown, when they are ready for use, the fisherman, in hauling the fish, taking hold of the line at the outside of the rail, and therefore not disturbing the latch, except in case of changing lines.

Having thus described my invention,

What I claim as new, and desire to secure by Letters Patent, is—

A latch, as constructed, with stock D, the catches a a, and channels for the lines c c, substantially as and for the purposes specified.

CHAS. S. H. FOSTER.
